HANDLE AND LOCK COVER

Ray F. Jordan, Corydon, Ind.

Application July 29, 1949, Serial No. 107,541

6 Claims. (Cl. 70—455)

1

This invention relates to an improved cover for the handles and key locks of such as the doors of automobiles, for protection of the lock structure against infiltration of snow, rain or water splashed from the road and against resultant rusting or freezing of the lock, rendering the lock inoperable by its key, the primary object of the invention being to provide a more efficient and practical cover of this kind which can be installed more securely and is easily removable even when coated with ice.

Another important object of the invention is to provide a cover of the character indicated above which does not require removal from the handle to enable opening or closing of the associated door by means of the handle and need be only partially removed or displaced to enable insertion and removal of the key in the lock.

A further important object of the invention is the provision of a cover of the character indicated above which incorporates an absorbent pad to engage the keyhole portion of the handle lock in a manner to absorb any moisture which may have accumulated thereon, and thereby prevent the freezing of such moisture which might otherwise render the lock inoperative.

Other important objects and advantages features of the invention will be apparent from the following description and the accompanying drawings, wherein, for purposes of illustration only, a specific embodiment of the invention is set forth in detail.

In the drawings:

Figure 1 is a fragmentary side elevation of an automobile having door-locking handles, with a device in accordance with the present invention installed on one of the handles;

Figure 2 is an enlarged horizontal section taken on the line 2—2 of Figure 1;

Figures 3 and 4 are vertical transverse sections taken on the lines 3—3 and 4—4, respectively, of Figure 1;

Figure 5 is an enlarged perspective view of the resilient wire frame.

Referring in detail to the drawings, wherein like numerals refer to like parts throughout the several views, the numeral 6 generally designates a form of handle present on certain present models of automobiles, involving a horizontal longitudinally-bowed intermediate portion 7 spaced from the outboard surface 8 of the associated door 9, the intermediate portion 7 terminating at one end in an inboardly-directed terminal 10 fixed to the door, and terminating at the opposite end in a cylindrical, inboardly-

2

directed terminal 11 fixed to the door. The cylindrical terminal 11 contains the door lock mechanism including the push-button 12 normally projecting outboardly beyond the cylindrical terminal 11 and formed with the keyhole 12' to accommodate a key (not shown). While the invention is especially applicable to this type of locking handle, it is also applicable to other forms of locking handles wherein the key lock mechanism is at one end of the handle.

The herein-illustrated cover, which is generally designated 15, comprises a spring wire frame 16, which can be formed from a single length of suitable gauge wire, to provide a circular loop or ring 17 to loosely encircle the inboard end of the cylindrical terminal 11 and engage the door surface 8, the ring 17 being slightly open at one side with the ends bent at right angles relative to the ring to define parallel portions 18, 18 long enough to reach to a point near the inboard surface of the intermediate handle portion 7, as shown in Figure 2. The parallel portions 18 merge into parallel longitudinal portions 19, 19 long enough to reach to the inboard surface of the handle terminal 10, and bowed or not to conform to the inboard surface of the intermediate handle portion 7. The ends of the longitudinal portions 19, 19 remote from the ring 17 are connected by an angulated loop 20 of a shape and aperture to conformably embrace the sides and outboard surface of the handle terminal 10.

The longitudinal portions 19, 19 are spaced from each other preferably at a distance less than the width of the intermediate portion 7 of the handle, so that they engage the sides of the inboard surface of the intermediate handle portion 7 when the device is installed and hold the device in place, and require to be spaced apart to enable removal of the device from the handle.

Facilitating removal of the device from a handle 6 and serving also to increase the security of the grip of the device upon the handle are ears 21, 21 formed in one frame portion 19 and one or more similar ears 22 formed in the other frame portion 19, preferably between the ears 21, 21. These ears preferably project slightly in laterally-inward directions relative to the portions 19, 19, so as to act as fingers grippingly engaging behind portions of the inboard surface of the intermediate handle portions 7, thereby increasing the security of the installation. These ears are sufficiently spaced from each other on the frame portions 13, 19 to enable insertion of the fingers or a suitable tool between them in order to move

them apart and thereby spread apart the frame portions 19, 19 sufficiently to enable the frame 16 to be pulled off the handle 6.

A boot 23, made of thin flexible material, such as rubber or weatherproof fabric, comprises a cylindrical portion 24 adapted to loosely surround the cylindrical handle terminal 11, as shown in Figure 2, and having a closed outer end 25 having secured to its inner side an absorbent pad 26 positioned to bear against the outer end of the push-button 12, and cover and close the keyhole 12' therein to prevent entry of moisture therein and to absorb any moisture already present. The edges of the open inboard end of the cylindrical boot portion 24 are trained over and secured to or otherwise suitably secured to the ring 17 of the frame 16, as indicated at 27.

The boot 23 further comprises a trough or channel-shaped intermediate portion 28 shaped and sized to conformably engage the handle intermediate portion 7, as shown in Figure 2, with the edges 29 of its sides secured to the longitudinal frame portions 19, 19 and around the loop 20 like the edge of the inboard end of the cylindrical boot portion 24.

To install the cover 15, the frame 16 is spread to receive the handle 6 by pulling the ears 21 and 22 apart and pushing the cover onto the handle with the ring 17 circumscribed on the cylindrical handle terminal 11 and the ears 21 and 22 at the upper and lower surfaces of the intermediate handle portion, the pushing being continued until the ears and the longitudinal frame portions 19, 19 engage behind the intermediate hand portion 7 and the loop 20 embraces the handle terminal 10. The cover 15 will then be properly secured on the handle 6 with the absorbent pad 26 closing the keyhole.

To insert a key (not shown) in the lock keyhole 12', the cylindrical boot portion 24 is grasped and pulled in an outboard direction until the keyhole 12' is exposed, whereupon the key may be inserted and turned to open the lock. The push-button may be operated, while the lock is unlocked, without displacing the cylindrical cover portion 24, due to the flexibility thereof. In the event that ice covers the device and resists manual displacement thereof, an instrument, such as a key or a screw driver, can be inserted between the ring 17 and the door surface 8 to easily pry the ring loose, whereupon the cover can be partially displaced to permit use of the key, or entirely removed without difficulty.

I claim:

1. A cover for use on an elongated handle having an inboardly-directed terminal on one end, a lock member projecting outboardly from said one end and having a keyhole exposed at the outboard side of said handle, said cover comprising a spring wire frame comprising laterally-spaced longitudinal members adapted to be spread apart to pass the handle therebetween and to be released to contract and grip inboard portions of the handle, a ring on and joining said longitudinal members at one end and arranged to encircle said terminal, a loop at and joining the opposite ends of said longitudinal members and shaped to embrace the end of the handle opposite the said terminal, and a flexible boot open at its inboard side and having its inboard edges secured to said ring, said longitudinal members and said loop of said frame and adapted to enclose said handle and the terminal thereof and protect said keyhole while said cover is in place on the handle.

2. A cover for use on an elongated handle,

having an inboardly-directed terminal on one end, a lock member projecting outboardly from said one end and having a keyhole exposed at the outboard side of said handle, said cover comprising a spring wire frame comprising laterally-spaced longitudinal members adapted to be spread apart to pass the handle therebetween and to be released to contract and grip inboard portions of the handle, a ring on and joining said longitudinal members at one end and arranged to encircle said terminal, a loop at and joining the opposite ends of said longitudinal members and shaped to embrace the end of the handle opposite the said terminal, and a flexible boot open at its inboard side and having its inboard edges secured to said ring, said longitudinal members and said loop of said frame and adapted to enclose said handle and the terminal thereof and protect said keyhole while said cover is in place on the handle.

3. In combination, a handle comprising an elongated portion having inboard terminals adapted to be secured to a door and to space said elongated portion from said door, a lock member projecting outboardly from said handle in the region of one of said terminals and having a keyhole at its outboard end, a cover for said handle comprising a spring wire frame comprising an open ring encircling said one terminal and said lock member in position to contact said door, said ring having ends, two spaced longitudinal portions proceeding from said ring ends and extending along opposite sides of and behind said elongated portion, and a loop connecting the ends of said longitudinal portions opposite said ring and embracing the other terminal, and a flexible boot having a channel portion receiving and covering said elongated handle portion, said channel portion having edges secured to the longitudinal frame portions.

4. In combination, a handle comprising an elongated portion having inboard terminals adapted to be secured to a door and to space said elongated portion from said door, a lock member projecting outboardly from said handle in the region of one of said terminals and having a keyhole at its outboard end, a cover for said handle comprising a spring wire frame comprising an open ring encircling said one terminal and said lock member in position to contact said door, said ring having ends, two spaced longitudinal portions proceeding from said ring ends and extending along opposite sides of and behind said elongated portion, and a loop connecting the ends of said longitudinal portions opposite said ring and embracing the other terminal, a flexible boot comprising an elongated channel portion conformably covering said elongated handle portion, said channel portion having longitudinal edges secured to and along said longitudinal frame portions, and a cylindrical portion at the end of said channel portion enclosing said one handle terminal, said cylindrical portion having an open inboard end having edges secured to and around said ring and having a closed outboard end registered with said keyhole and the outboard end of said lock member.

5. In combination, a handle comprising a elongated portion having inboard terminals adapted to be secured to a door and to space said elongated portion from said door, a lock member pro-

jecting outboardly from said handle in the region of one of said terminals and having a keyhole at its outboard end, a cover for said handle comprising a spring wire frame comprising an open ring encircling said one terminal and said lock member in position to contact said door, said ring having ends, two spaced longitudinal portions proceeding from said ring ends and extending along opposite sides of and behind said elongated portion, and a loop connecting the ends of said longitudinal portions opposite said ring and embracing the other terminal, a flexible material boot comprising an elongated channel portion conformably covering said elongated handle portion, said channel portion having longitudinal edges secured to and along said longitudinal frame portions, and a cylindrical portion at the end of said channel portion enclosing said one handle terminal, said cylindrical portion having an open inboard end having edges secured to and around said ring and having a closed outboard end registered with said keyhole and the outboard end of said lock member, and an absorbent pad secured to the inboard side of said closed outboard end and bearing against the outboard end of said lock member so as to protectively engage said keyhole, said cylindrical boot portion and said frame ring being flexible in an outboard direction relative to said frame and said boot and away from the door in a manner to uncover the outboard end of said lock member without disengaging the cover from the handle to provide access to the keyhole.

6. In combination, a handle comprising an elongated portion having inboard terminals adapted to be secured to a door and to space said elongated portion from said door, a lock member projecting outboardly from said handle in the region of one of said terminals and having a keyhole at its outboard end, a cover for said handle

30

35

40

comprising a spring wire frame comprising an open ring encircling said one terminal and said lock member in position to contact said door, said ring having ends, two spaced longitudinal portions proceeding from said ring ends and extending along opposite sides of and behind said elongated portion, and a loop connecting the ends of said longitudinal portions opposite said ring and embracing the other terminal, a flexible material boot comprising an elongated channel portion conformably covering said elongated handle portion, said channel portion having longitudinal edges secured to and along said longitudinal frame portions, and a cylindrical portion at the end of said channel portion enclosing said one handle terminal, said cylindrical portion having an open inboard end having edges secured to and around said ring and having a closed outboard end registered with said keyhole and the outboard end of said lock member, and an absorbent pad secured to the inboard side of said closed outboard end and bearing against the outboard end of said lock member.
